UNITED STATES PATENT OFFICE.

ARCHIBALD KELSO, OF PITTSBURG, PENNSYLVANIA.

FLUID-MOTOR.

963,581.

Specification of Letters Patent. Patented July 5, 1910.

Application filed October 14, 1909. Serial No. 522,523.

To all whom it may concern:

Be it known that I, ARCHIBALD KELSO, a citizen of the United States, and a resident of Pittsburg, in the county of Allegheny and State of Pennsylvania, have invented a new and Improved Fluid-Motor, of which the following is a full, clear, and exact description.

This invention relates to a motor of the 10 reciprocatory rotary type, to be operated by any suitable fluid, such as water under a head.

An object of this invention is to provide a device which will be simple in construction, strong, durable, and positive and efficient in its operation.

A further object of this invention is to provide a device having a rotary element, with means for automatically reversing the 20 rotation of said element.

A still further object of this invention is to provide a device with a reciprocatory rotary element, with means for supplying an operating fluid to either side of said element, and 25 means for sharply reversing the flow of said fluid.

These and further objects, together with the construction and combination of parts, will be more fully described hereinafter and 30 particularly set forth in the claims.

Reference is to be had to the accompanying drawings forming a part of this specification, in which similar characters of reference indicate corresponding parts in all 35 the views, and in which—

Figure 1 is a top plan view of my device; Fig. 2 is a vertical section through the center of the same; Fig. 2^a is a detail view in elevation, of a portion of the piston and the 40 shaft to which it is connected; Fig. 3 is a horizontal section, showing the movable parts in one position; Fig. 4 is a view similar to Fig. 3, showing the movable parts in their opposite position; Fig. 5 is an enlarged 45 sectional detail view of the valve casing, on the line 5—5 of Fig. 4; Fig. 6 is a bottom plan view of the valve-operating parts, corresponding to the position of the piston indicated in Fig. 3; Fig. 7 is a bottom plan 50 view similar to Fig. 6, corresponding to the position of the parts just before they reach the position indicated in Fig. 4; Fig. 8 is a vertical section showing in enlarged detail the valve-throwing mechanism; Fig. 9 is 55 a plan view, showing in enlarged detail a portion of the valve-throwing mechanism;

and Fig. 10 is a detail view of the valve-operating lever.

Referring more particularly to the separate parts of the device, 1 indicates a supporting frame, which may be of any suitable form and material, and on which is supported a motor casing 2. The motor casing 2 comprises a cylindrical body portion 3 and a pair of heads 4 and 5 having cylindrical flanges overlying the body portion 3 and being tied together by suitable bolts 8 extending through perforations in the outstanding flanges of the heads. The head 5 has a plurality of outstanding lugs 6, provided with perforations through which extend tie-bolts 7, whereby the device is secured to any suitable support, such as a bracket on a washing machine. The head 5 is also provided with a central aperture 75 through which extends a shaft 9, which is also journaled in a bearing formed in the opposite head by insetting the head at 10. A suitable stuffing box 11 is provided where the shaft 9 passes through the head 5, to 80 prevent the outflowing of the operating fluid within the casing 2. The shaft 9 is provided with a vane 12, which is preferably formed integral therewith, and is of such a size as to almost contact with the inner surface of the cylindrical body portion 3. In 85 order to make the contact perfect and prevent any possible leakage of the operating fluid by the vane 12, this vane is flanked on either side with flexible packing strips 13 and 14, which are secured to the vane 12 by means of plates 15 and 16, which are tied to the vane 12 by bolts 17 that pass through alined openings. The packing strips 13 and 14 are of slightly greater size 90 than the plates 15 and 16, and the vane 12, so that they form overlapping flanges on all sides, to wipe against the surfaces of the heads 4 and 5 and the body portion 3, forming a perfectly fluid-tight joint. These 100 parts taken together are adapted to form a piston, which rotates with the shaft 9.

Extending from the inner surface of the casing 3 to the outer surface of the shaft 9, there is provided a partition 18, which has a packing member 19 engaging the outer surface of the shaft 9, so that a perfect fluid-tight joint is formed between the casing 3 and the shaft 9. Forming a part of this wall or partition 18, there is provided 110 a valve casing 20, which has an outlet 21 to an exhaust pipe 22, and a similar inlet 23

to a supply pipe 24. This valve casing is also provided with a pair of openings 25 and 26 communicating with the interior of the motor casing 2 on opposite sides of the 5 partition 18.

For the purpose of alternately connecting the openings 25 and 26 with the exhaust pipe 22 and the supply pipe 24, there is provided a valve 27, which is rotatably supported in 10 the valve casing 20, and has a valve spindle 28 which extends through a suitable stuffing box 29. The valve 27 is provided with two 15 passages 30 and 31, which may be of any form suitable to connect either the passages 23 and 26 and the passages 21 and 25, or the passages 21 and 26 and the passages 23 and 25. By this means, the fluid entering 20 through the supply pipe 24 can be deflected to either side of the partition 18, thereby causing the piston to rotate away from this 25 side of the partition 18. In the meantime the opposite side of the partition 18 is open to the exhaust pipe 22, permitting the fluid back of the piston to pass out therethrough. 30 The different positions of the valve to connect the different passages are illustrated clearly in Figs. 3 and 4, the passage of the fluid in each case being illustrated by the arrows. The side of the valve 27 which 35 co-operates with the inlet opening 23 is broad, so as to lessen the amount of fluid which flows through, while the side which co-operates with the exhaust opening 21 is narrow, so as to increase the flow of fluid. 40 In order to make the action of the reversion of the valve and thereby the reversion of the piston, automatic, there is provided a connection by means of which the valve is operated by the piston shaft, 45 thus saving the piston from striking at either end of its stroke. The valve spindle 28 is angular at 32, so as to form a convenient locking surface, which is engaged by a lever 33. This lever 33 is of peculiar 50 shape and form, and is provided preferably with cam surfaces, as at 34 and 35, and is also provided on the side facing the head 5 with a pair of cam lugs 36 and 37.

Secured to the shaft 9 by any suitable 55 means, such as a dowel-pin 38, there is provided a concentric ring 39, which supports a shifter 40. The shifter 40 is provided at the ends thereof with cam lugs 41 and 42, which are adapted to come in engagement 60 respectively with the cam lugs 36 and 37 on the lever 33, at alternate rotary reciprocations of the shaft 9 and the piston thereon, and are for the purpose of holding the lever against movement until the piston has

reached the end of its rotation. 65 In order to throw the lever 33 after the cam lugs have passed by each other, there is provided a member 43, which is slidably supported on the shifter 40 by means of a

guide groove 44 thereon engaging with a flange 45 on the shifter 40. The member 43 has downwardly-extending flanges 46 at each end, which are adapted to pass through slots 47 on the shifter 40, and engage a spring 48 retained in a receptacle 49 in the shifter 40, 70 and adapted to alternately abut against the heads of said receptacle. Extending upwardly from the opposite surface of the member 43, there are provided at the ends thereof outstanding cam lugs 50 and 51, 75 which are adapted to engage respectively the cam surfaces 34 and 35 on the lever 33. The member 43 is held in position on the shifter 40 by means of a plate 52, which is secured in any well known manner on the shifter 80 40, as by means of a set screw 53.

The shaft 9 has secured thereto an extension shaft 54, by means of which the power is transmitted from the motor to any suitable source, such as a washing machine. 85

The operation of the device will be readily understood from the above description. Starting with the parts in the position indicated in Fig. 3, the operating fluid, such as water under a head, will be supplied 90 through the pipe 24, the opening 23, the passage 31 and the opening 26, into the motor casing on the under side of the partition 18, as indicated by the arrow. The operating fluid will force the piston away from the 95 partition 18, so as to rotate with the shaft 9. The position of the valve 27 will also permit the fluid on the opposite side of the piston to pass out through the opening 25, the valve passage 30, and the opening 21, into 100 the exhaust pipe 22. When the piston approaches the end of its stroke, as indicated in Fig. 4, the lug 41 on the shifter 40 will have come in contact with the lug 36 on the lever 33. At the same time, the lug 50 on 105 the member 43 will have come in contact with the cam surface 34 on the lever 33. The continued motion of the piston will gradually pass the lug 41 by the lug 36, at the same time holding the member 43 110 stationary against the tension of the spring 48. When the lug 41, which engages the lug 36 and prevents the lever 33 from rotating, slips by the lug 36, then the member 43 will be shifted rapidly by the spring 48, 115 which is now under a high tension, in such a manner as to shift the lever 33 into the position indicated in Fig. 6. By this means, the valve 27 will be shifted from the position indicated in Fig. 3 to the position indicated in Fig. 4, connecting the opposite side of the partition 18 with the supply pipe 24, and permitting the side which was previously the power side to communicate 120 with the exhaust pipe 22. When this occurs, the operating fluid will pass from the pipe 24 through the opening 23, the passageway 30, and the opening 25, to the back side of the piston, creating a motive impulse between the upper side of the parti- 125

tion 18 and the piston. This will cause the piston to rotate in the opposite direction.

When the piston approaches the end of its stroke, the lug 42 on the shifter 40 will come in contact with the lug 37 on the lever 33, preventing the lever from rotating until the lug 42 completely passes the lug 37. In the meantime, however, the lug 51 on the member 43 will have engaged the cam surface 35 on the lever 33, thereby holding the member 43 stationary against the tension of the spring 48. When the shifter 40 has rotated a sufficient distance to cause the lug 42 to slip by the lug 37, the member 43 will be automatically snapped along its guide 45 by the compressed spring 48, thereby shifting the lever 33, and with it the valve 27, from the position indicated in Fig. 4 to the position indicated in Fig. 3. This operation is continuous, the piston rotating first in one direction and then in the other, the direction being automatically reversed at the end of each rotation, thereby producing a reciprocatory rotary motion, which is highly desirable in certain classes of devices, such as washing machines.

Having thus described my invention, I claim as new and desire to secure by Letters Patent:

1. In a motor, the combination with a casing, of an oscillating piston in said casing, a valve for controlling the flow of operative fluid to said piston, a lever for operating said valve, cam lugs on said lever, a shifter connected to said piston, cam lugs on said shifter adapted to engage said cam lugs on said lever to hold said lever stationary during a portion of a revolution of said piston, and means on said shifter for engaging said lever, to operate the same.

2. In a motor, the combination with a casing, of an oscillating piston in said casing, a valve for controlling the flow of operative fluid to said casing, a lever for operating said valve, a shifter connected to said piston, means on said shifter for engaging said lever, to hold said lever stationary during a portion of a revolution of said piston, a member slidably supported on said shifter and adapted to engage said lever, and a spring connected to said shifter and said member, adapted to accumulate a potential force to operate said member.

3. In a motor, the combination with a casing, of an oscillating piston in said casing, a valve for controlling the flow of fluid to said casing, a lever for operating said valve, a shifter connected to said piston, means on said shifter adapted to hold said lever stationary during a portion of a revolution of said piston, a receptacle connected to said shifter, having openings in the heads thereof, a spring contained in said receptacle, a

member slidably connected to said shifter, lugs on said member adapted to pass through 65 said openings and engage said spring, and means on said member for engaging said lever.

4. In a motor, the combination with a casing, of an oscillating piston in said casing, 70 a valve for controlling the flow of fluid to said casing, a lever for operating said valve, a shifter connected to said piston, means for holding said lever stationary during a portion of a revolution of said piston, a receptacle connected to said shifter and having 75 slotted heads thereon, a spring contained in said receptacle, a member slidably engaging said shifter, lugs on said member adapted to pass through said slots in said 80 receptacle and engage said spring at each end thereof, and cam lugs on said member adapted to engage said lever.

5. In a motor, the combination with a casing, of an oscillating piston in said casing, a 85 valve for controlling the supply of motive fluid to said casing, a lever for operating said valve, cam lugs on said lever, a shifter connected to said piston, cam lugs on said shifter adapted to alternately engage said 90 cam lugs on said lever, to hold said lever stationary during portions of a revolution of said piston, a member movably secured to said shifter and adapted to remain stationary during a portion of a revolution of said 95 shifter, and a spring for bringing said member back into its original position relative to said shifter.

6. In a motor, the combination with a casing, of an oscillating piston in said casing, 100 a partition in said casing, a valve casing connected to said partition and having openings communicating with each side of said piston, a supply pipe connected to said valve casing, an exhaust pipe connected to said 105 valve casing, a valve adapted to connect either side of said partition with either said supply pipe or said exhaust pipe, a lever for operating said valve, cam lugs on said lever, a shifter connected to said piston, cam 110 lugs on said shifter adapted to alternately engage said cam lugs on said lever, to hold said lever stationary during a portion of a revolution of said piston, a member movably connected with said shifter, cam lugs on 115 said member engaging said lever, and a spring on said shifter adapted to yieldingly hold said member against said lever at the ends of the rotation of said piston.

In testimony whereof I have signed my 120 name to this specification in the presence of two subscribing witnesses.

ARCHIBALD KELSO.
